Fig. 1

Fig. 2

FIG. 3

FIG. 4

FIG. 1 is a front perspective view of an input/output console for a computer showing my new design;

FIG. 2 is an elevational view taken from the left side thereof, the right side being substantially the same as the left side shown except for the omission of the key receptacles;

FIG. 3 is a rear elevational view thereof; and

FIG. 4 is a front perspective view thereof illustrating the console in one mode of operation, the keyboard mounting plates being separately shaded for contrast.

I claim:

An ornamental design for an input/output console for a computer, as shown and described.
